FIG.4

FIG. 1 is a front elevational view showing a toy figure embodying my new design;

FIG. 2 is a rear elevational view of FIG. 1;

FIG. 3 is an elevational view taken from either side of FIG. 1;

FIG. 4 is a bottom plan view thereof; and

FIG. 5 is a top plan view thereof.

This application is a division of co-pending application Ser. No. D. 15,546, filed Jan. 21, 1969.

I claim:

The ornamental design for a toy figure, as shown and described.
